UNITED STATES PATENT OFFICE.

JOSEPH S. POWER, OF DAYTON, OHIO, ASSIGNOR TO THE DAVIS SEWING MACHINE COMPANY, OF DAYTON, OHIO, A CORPORATION OF DELAWARE.

WASHING MACHINE.

Application filed March 24, 1921. Serial No. 455,271.

To all whom it may concern:

Be it known that I, JOSEPH S. POWER, a citizen of the United States, residing at Dayton, in the county of Montgomery and 5 State of Ohio, have invented certain new and useful Improvements in Washing Machines, of which the following is a specification, reference being had therein to the accompanying drawing.

10 My invention relates to washing machines, and in particular to a driving mechanism for washing machines. It will be understood, however, that the application of my mechanism is broader than 15 simply that of operating washing machines and that it is applicable to all classes of machinery.

The object of my invention is to provide a driving mechanism to reciprocate 20 any given part during a portion of the time of its operation and to bring that part to rest without stopping the driving shaft. It is a further object of my invention to provide means for bringing the driven member 25 from its operative to its inoperative position, unlocking it from its operative position and locking it in its inoperative position. By inoperative position, I mean that the driven member is brought to a substantial 30 rest, although there may be a slight movement which for practical purposes, such as in washing machine constructions, will be so slight as not to be of any consequence.

35 It is a further object that when the tub is in this position of substantial rest it is brought to a predetermined and substantially locked position thus eliminating the necessity of the operator moving the tub, which is frequently heavy with the water 40 and clothes, to a horizontal position where it can be suitably attended to and drained. It is my object to eliminate this feature which is a present disadvantage of operating mechanisms now known in the art for 45 this purpose.

It is a further object of my invention to provide a means of throwing out of operative position the unlocking mechanism 50 after it has once unlocked and permitted of the locking of the mechanism in any position.

It is a further object of my invention to provide, in combination with this driving 55 mechanism, a flexible driving rod or con-

necting rod which will permit of the variations in position in such driving mechanism, secure a suitable alignment and absorption of stresses and strains, and will also permit of the slight movement which 60 may be imparted to the driven member such as a connecting rod when the driven member is brought to a position of substantial rest, thus taking up whatever movement there may be without communicating it to 65 the tub or other part which is being ultimately driven by this mechanism.

Referring to the drawings:

Fig. 1, is a plan view of the mechanism with a portion of the parts cut away and 70 shown in section;

Fig. 2, is a plan view of the driving portion of the mechanism in its neutral or inoperative position;

Fig. 3, is a section of the mechanism for 75 locking and unlocking the driving mechanism when it is in its position to operate the driven member;

Fig. 4, is a section of the driving mechanism when in a position of substantial rest 80 with the driven member, at the time when the centers of the driving member and the point of connection of the driven member substantially coincide;

Fig. 5, is a side elevation of a washing 85 machine with this mechanism applied to it.

Referring to the drawings, 1 is a drive shaft that has a square head 2 for insertion in a square aperture 3 of the crank member 4. This crank member is pivoted on the 90 pivot 5 to the plate 6. The point of pivoting is centrally located on 6. Eccentrically located on the lower face of 6 at 7 is a ball 8 of a ball and socket connection 9 which constitutes one end of the flexible connecting link or connecting rod 10. This crank member 4 has a locking pin 11 which is normally held in engagement with an aperture 12 or an aperture 13 by a spring 14 carried in a housing 15 of the crank member 4. 95

The upper end of 11 has a head 16 and a collar 17 which is engaged by the bifurcated free end 18 of the unlocking member 19. The lower end of 11 has a nose 105 20 that is tapered to engage with the tapering aperture 12 or 13. 19 is fastened to a shaft 21 that is actuated by a handle 22. This handle has a shoulder 23 on one side thereof in the nature of a cam on either face 110

of which the pawl 24 engages by reason of the pressure of the spring 25 carried in the housing 26 that is stationary. The object of having this locking mechanism is to 5 maintain the arm 19 in either its inoperative or operative position as will be hereinafter described.

Referring to the connecting rod 10, it will be observed that it is composed of a ball and 10 socket connection which terminates in a threaded head 27 about which is wound the spring 28 in the grooves 29 within the casing 30 that is fastened by the screws 31 to 10. This serves to guide the spring and to 15 retain the spring within the grooves 29 of the threaded head 27. This casing 30 slides upon the cylindrical member 32 which constitutes the other end of the connecting rod. This member 32 also has a threaded head 20 33 with grooves 34 in which the spring 28 is wound. This end 32 has a cup-shaped bearing member 35 in the bottom of which is a wooden bearing 36 engaging with the head of the ball 37. Surrounding the lower 25 surface of the ball is the collar 38 that is threaded at 39 into the cup-shaped member 35 and maintains the ball in position in engagement with the wood 36. This permits of an adjustable bearing to take up any wear. 30 The adjustment is fixed by the set screw 40. The ball 37 is attached to any member to be driven as 41 which may be a washing machine tub or any other similar mechanism.

The application of this driving mechanism to an actual machine will be seen in 35 Figure 5. 42 is a frame of the washing machine in which is suspended a tub 43 carrying braces 41 which constitute part of the tub. The tub is designed to be reciprocated 40 about the pivotal point 44. The driving shaft 1 is actuated by a suitable motor 45. The direction of motion is changed by the gear shift 46 operated by the handle 47.

45 *Method of operation.*

When the power is turned on to rotate the driving shaft 1 it rotates about its axis the crank member 4. If the parts are in the 50 position shown in Figure 1 and Figure 3, the point of connection of the connecting rod to the plate which is being driven by the crank member will be offset from the center of the driving shaft and as the crank is thus formed the connecting rod will be reciprocated as its point of connection through 55 the ball and socket 8 and 9 follows in the path of a circle about the axis of 1 as a center.

If the unlocking member 19 has its bifurcated head 18 swung into the path of the 60 latch 11 by the handle 22 and maintained in that position by the pawl 24, this bifurcated end will come in contact with the collar 17 and thus lift the pin 11 as 18 comes in contact with the sloping shoulder on the 65 underside of the head 16. This action com-

presses the spring 14. As the crank member 4 and the driving shaft 1 continue to rotate the engagement of the head 20 with the aperture 12 having been broken, the plate 6 will remain stationary together with 70 the driven connecting rod until the head 20 drops into the aperture 13. When this occurs the head 18 will be in the position shown in dotted lines at the left hand in Figure 1. As the shaft 1 continues to rotate with the 75 crank member 4, the engagement having been made with the plate 6 by 11 falling into 13 through the pressure of the spring 14, the plate 6 will rotate until the head 16 strikes the right hand side of the bifurcated head 80 18 and moves it into the full line position shown in Figure 1 in which position it will remain, being locked in that position by the pawl 24.

When this arrangement of the parts has 85 been secured by 11 being thrust into 13 by the spring 14, it will be found that the parts have assumed the position shown in Figure 4, where the ball is substantially beneath the driving shaft so that the rotation of that 90 shaft will impart a very slight movement, if any, to the connecting rod. It will be understood that any such movement will be absorbed by the flexible connection which constitutes this connecting rod as the casing 30 can move with respect to 32 when the spring 28 is compressed or expanded to take up the variations in thrust. It will be understood that when the parts are in the position as shown in full lines in Figure 100 1 and as in Figure 3, the tub or other member connected to 41 will be reciprocated. The strains, shocks and stresses of this reciprocation, particularly that of picking up the initial load when starting, will be absorbed by the connecting rod. This permits of the employment of wooden bearings 105 and the sulphur lining of the connecting rod with the minimum wear and tear upon the joints and connections and the shocks and strains incident thereto.

It will be observed that there is a novel construction which permits of bringing the mechanism from full operation to neutral position, which permits of the absorption 115 of stresses, strains and shocks, and which permits of the elimination entirely of any clutch mechanism with its attendant complications and difficulties.

While I have shown and described certain features as constituting my invention, it will be understood that parts have been shown for purposes of illustration only, and that I do not desire to be limited to such details, as obvious modifications will occur 120 to a person skilled in the art.

Having thus fully described my invention, what I claim as new and desire to secure by Letters Patent, is:

1. In combination, a driving shaft, a 130

- crank member connected thereto, a driving disk mounted on said crank member, means on said disk eccentrically thereof for the attachment of a driven member, a driven member, means on said driving disk and crank member for locking the several parts respectively to reciprocate the driven member and to maintain it in substantial inoperativeness while the remainder of the parts rotate continuously, and means for unlocking the crank member and disk. 5
2. In combination, a driving shaft, a crank member connected thereto, a driving disk mounted on said crank member, means on said disk eccentrically thereof for the attachment of a driven member, a driven member, means on said driving disk and crank member for locking the several parts respectively to reciprocate the driven member and to maintain it in substantial inoperativeness while the remainder of the parts rotate continuously, means for unlocking the crank member and disk, and means for maintaining the unlocking means 25 in its inoperative position. 15
3. In combination, a driving shaft, a crank member connected thereto, a driving disk mounted on said crank member, means on said disk eccentrically thereof for the attachment of a driven member, a driven member, means on said driving disk and crank member for locking the several parts respectively to reciprocate the driven member and to maintain it in substantial inoperativeness while the remainder of the parts rotate continuously, means for unlocking the crank member and disk, and means for bringing the unlocking means into its operative position to effect the unlocking. 35
4. In combination, a driving shaft, a crank member connected thereto, a driving disk mounted on said crank member, means on said disk eccentrically thereof for the attachment of a driven member, a driven member, means on said driving disk and crank member for locking the several parts respectively to reciprocate the driven member and to maintain it in substantial inoperativeness while the remainder of the parts rotate continuously, means for unlocking the crank member and disk, means for bringing the unlocking means into its operative position to effect the unlocking, and means for maintaining the unlocking mechanism in an inoperative position after it has effected the unlocking of the disk and crank member. 55
5. In combination, a driving shaft, a crank member connected thereto, a driving disk mounted on said crank member, means on said disk eccentrically thereof for the attachment of a driven member, a driven member, means on said driving disk and crank member for locking the several parts 60
- respectively to reciprocate the driven member and to maintain it in substantial inoperativeness while the remainder of the parts rotate continuously, means for unlocking the crank member and disk, means for bringing the unlocking means into its operative position to effect the unlocking, means for maintaining the unlocking mechanism in an inoperative position after it has effected the unlocking of the disk and crank member, and means for moving the unlocking member into its fixed inoperative position. 70
6. In combination, a driving shaft, a crank member mounted thereon, a disk member pivotally mounted on said crank, a driven member mounted on said disk, a plunger carried by said crank member adapted to engage with apertures in said disk, whereby when the plunger is engaged with one of said apertures the point of connection of the driven member with the disk may be located substantially on the center of the driving shaft or eccentrically thereof as desired. 80
7. In combination, a driving shaft, a crank member mounted thereon, a disk member pivotally mounted on said crank, a driven member mounted on said disk, a plunger carried by said crank member adapted to engage with apertures in said disk, means of effecting the unlocking of said disk and crank member, and means for effecting the locking of said members to one another, whereby when the plunger is engaged with one of said apertures the point of connection of the driven member with the disk may be located substantially on the center of the driving shaft or eccentrically thereof as desired. 90
8. In combination, a driving shaft, a crank member mounted thereon having an aperture on one side thereof, a pin adapted to travel in said aperture, resilient means in said aperture surrounding said pin to keep it in its outermost position, a head on said pin, an unlocking arm having a bifurcated head for engaging with the head of the pin to lift it in said aperture, a shaft connected to said unlocking arm, a handle to operate said shaft, a cam on said handle, and a spring pressed pawl to engage with the cam for maintaining said handle in unlocking and inoperative positions; a disk pivoted to said crank member eccentrically of the center of the driving shaft, a driven member connected to said disk eccentrically of its point of connection to the crank member, said disk having apertures for receiving the locking pin to maintain the parts so that the center of connection of the driven member is the eccentric of the center of the driving member and so that the respective centers just mentioned substantially coincide as desired, whereby the 105
- 110
- 115
- 120
- 125
- 130

driven member may be reciprocated and rotated and also maintained in a substantially inoperative position.

9. In combination, a driving shaft, a
5 crank member connected thereto, a driving
disk mounted on said crank member, means
on said disk eccentrically thereof for the at-
tachment of a driven member, a driven
member, means on said driving disk and
10 crank member for locking the several parts
respectively to reciprocate the driven mem-
ber and to maintain it in substantial inoper-
ativeness while the remainder of the parts

rotate continuously, means for unlocking
the crank member and disk, and a tub con- 15
nected to the free end of the driven mem-
ber, whereby when the members are in their
operative position the tub will be recipro-
cated and in their inoperative position the
tub will be returned to its horizontal posi- 20
tion, locked in said position and only slight-
ly actuated.

In testimony whereof, I affix my signa-
ture.

JOSEPH S. POWER.
